CIGARETTE DISPENSER

James Orin Tankersley, Decatur, Ill.

Application February 23, 1939, Serial No. 258,025

1 Claim. (Cl. 312—84)

The invention relates to a cigarette dispenser and more particularly to a detachable dispenser for cigarettes adaptable for mounting on the instrument board within a vehicle body, being convenient for the delivery in single order of a cigarette into the hand of an operator of such dispenser, the undelivered cigarettes being confined so as to maintain the same fresh and readily obtainable at will.

A further object of the invention is the provision of a dispenser of this character, wherein the same is readily clamped to the dash or instrument board of a vehicle, particularly a motor vehicle, and occupies the least possible space in that it is compact and will successfully deliver cigarettes singly to an operator of the device.

A further object of the invention is the provision of a dispenser of this character, wherein the same can be readily filled when attached in place to the instrument or dash board of a vehicle without requiring the complete dismounting of such dispenser.

A further object of the invention is the provision of a dispenser of this character, which is simple in its construction, thoroughly reliable and efficient in operation, neat in appearance, readily and easily operated, and inexpensive to manufacture and install.

With these and other objects in view, the invention consists in the features of construction, combination and arrangement of parts as will be hereinafter more fully described, illustrated in the accompanying drawing, which discloses the preferred embodiment of the invention and pointed out in the claims hereunto appended.

In the accompanying drawing:

Figure 1 is a top plan view of the dispenser constructed in accordance with the invention.

Figure 2 is a front elevation thereof.

Figure 3 is a sectional view taken on the line 3—3 of Figure 1 looking in the direction of the arrows.

Figure 4 is a view similar to Figure 3 showing the dispenser with its dispensing gate or shutter in an adjusted position.

Similar reference characters indicate corresponding parts throughout the several views in the drawing.

Referring to the drawing in detail, the dispenser constituting the present invention comprises a hanger body formed with a flat top 10, side panels or cheeks 11 and laterally outstruck guides 12, respectively, the hanger body being open, front and back thereof, while at the rear-most edge of the top 10 is a channel-forming

flange 13, which is a continuation of the guides 12 struck outwardly at the panels or cheeks 11.

Removably fitted in the hanger body is a magazine-forming body 14 having a straight vertical front wall 15, side walls 16 and a relatively shallow vertical rear wall 17, respectively. From this shallow wall 17 is extended a forwardly inclined bottom 18, the front wall 15 being provided with an inwardly curved lower portion 19 which with the bottom 18 approach each other for providing therebetween a dispensing space or slot 20 for the dispensing of the contents of the dispenser in a manner presently described.

Mounted for vertical swing at the opening or slot 20 is an eccentrically disposed gate or shutter formed with a hollow shell portion 21 provided with an overrun top area 22 formed with a depressed seat or pocket 23 next to a directing lip 24, the gate or shutter being swingable upon a pivot 25 horizontally arranged and journaled in the side walls 16. The shell 21 carries within it an overbalancing weight 26 which urges the gate or shutter to closing position for the contact of the lip 24 with the curved lower portion 19. On contact of the lip 24 with this curved portion 19 of the front wall 15, the dispenser is closed, this being automatically brought about by the weight 26 within the shell portion 21 of the said gate or shutter. When it is desired to dispense a cigarette from the dispenser, an operator merely presses upon the shell portion 21 of the gate or shutter causing it to swing open and the cigarette 27 within the pocket 23 will by gravity roll upon the lip 24 into the hand of an operator of the dispenser engaging the said shell portion 21 of the gate or shutter.

The cigarettes within the magazine body 14 will be delivered or dispensed in single order in that the shell portion 21 turns in a manner to shut off further dispensing of the cigarettes other than the single one within the pocket 23 when the shutter or gate is swung to opening position.

On the top 10 of the hanger body is a screw clamp 28 adapted for clamping engagement with a cowl or instrument board of a vehicle, particularly a motor vehicle, a portion of the board being indicated at 29 and the clamping position of the dispenser is shown in detail at Figure 3 of the drawing.

The magazine body 14 is separable from the hanger body in that the side walls 16 carry out-turned guide flanges 30 fitting the guides 12 and the top 10 of the hanger body has an impression latching rib 31 which engages the back wall 17 when the magazine body is interfitted with the

hanger body, thus frictionally latching these together yet the magazine body is readily pulled from within the hanger body, the uppermost portion of the said magazine body being open so that on removal thereof it can be filled with cigarettes.

The bottom 18 has the downwardly curved overhanging edge 32 with respect to the shell portion 21 of the gate or shutter effecting a close joint relationship therebetween. The gate or shutter is shown in closed position in Figure 3 and in Figure 4 of the drawing in a dispensing position for effecting on the swing of the said gate or shutter the single dispensing or delivery of a cigarette from the dispenser.

When the magazine body is within the hanger body, the front wall 15 of the magazine body is disposed slightly inwardly or the marginal edge of the open front of said hanger body.

The magazine body at the back wall 17 has separable lip engagement at 33 with the channeled flange forming a continuation of the guides 12 at opposite sides of the hanger body.

The side walls 16 of the magazine body are extended downwardly to close the opposite ends of the pocket 23 throughout the movement of the shutter or gate. The cigarettes within the magazine body gravitate for single deposit within the pocket 23 so that on operating the gate or shutter a single delivery of the cigarette is assured while the lip 24 directs the delivering cigarette into the hand operating the shutter or gate, one hand only being required for the op-

eration of the gate or shutter and with the palm of the hand uppermost the cigarette being delivered rolls into the hand during the dispensing operation.

The dispenser, while adaptable for use in a vehicle, is also adaptable for use in connection with tables or other supports, as, for example, a card table or the like.

What is claimed is:

A dispenser for slender articles, comprising a body having a slotted substantially hopper shaped bottom, a tubiformed dispensing gate swingable in the slot in the said bottom and forming a hollow for a weight, a weight fixedly held and so disposed within the hollow in said gate as to normally urge the same in closing non-dispensing position, a lip extending from the gate for delivering an article from the body into the hands of an operator, the said gate being formed with a pocket next to the lip for reception of a single article from within the body when the gate is in non-dispensing position and adapted to deliver the single article onto the lip on the swinging of the gate to a dispensing position from non-dispensing position, and pivot ears formed on the gate for eccentric swingable mounting thereof on a horizontal axis, the gate being so constructed that in the non-dispensing position the slot in the bottom of the hopper is closed by the gate and its lip while in the dispensing position the slot is closed wholly by the body portion of the gate.

JAMES O. TANKERSLEY.
